UNITED STATES PATENT OFFICE.

MAURICE LUCIEN FRINGS, OF PARIS, FRANCE, ASSIGNOR TO SOCIÉTÉ MAURICE FRINGS ET CIE., OF PARIS, FRANCE, A CORPORATION OF FRANCE.

DESIGN FOR A REEL OR BOBBIN.

No. 39,254.

Specification for Design.

Patented April 7, 1908.

Application filed August 7, 1907. Serial No. 387,571. Term of patent 7 years.

To all whom it may concern:

Be it known that I, MAURICE LUCIEN FRINGS, a citizen of the Republic of France, residing at No. 32 Rue Vitruve, Paris, France, have invented a new, original, and ornamental Design for a Reel or Bobbin, of which the following is a specification, reference being had to the accompanying drawing, forming part thereof.

The figure is a perspective view of a reel or bobbin, showing my new design.

I claim:

The ornamental design for a reel or bobbin, as shown.

MAURICE LUCIEN FRINGS.
